JOHN WEIDIG, OF PHILADELPHIA, PENNSYLVANIA, ASSIGNOR TO WILLIAM W. LYMAN, OF WEST MERIDEN, CONNECTICUT.

Letters Patent No. 77,555, dated May 5, 1868.

IMPROVEMENT IN FRUIT-JARS.

The Schedule referred to in these Letters Patent and making part of the same.

TO ALL WHOM IT MAY CONCERN:

Be it known that I, JOHN WEIDIG, of the city of Philadelphia, and State of Pennsylvania, have invented a new and improved Cap or Stopper for Fruit or Preserving-Cans or Jars; and I do hereby declare that the following is a full, clear, and exact description of the same, reference being had to the accompanying drawing, and to the letters of reference marked thereon.

My invention consists in cutting or forming the margin of the top of the cap or stopper of a preserving-jar or any other into two or more cams or elevations and depressions, by means of which, together with a strap whose hook-shaped ends take under the rim of the neck of the jar or can, the stopper is forced or wedged tight upon the neck of the same.

On reference to the accompanying drawing, forming a part of this specification—

Figure 1 is a sectional view of the upper part of a preserving-jar or can, with the stopper of the same.

Figure 2 is a view showing the method of fastening the stopper to the jar.

Figure 3 is a perspective view of the stopper; and

Figure 4 is a perspective view of the stopper as at first constructed.

Similar letters refer to similar parts in the several views.

A is a fruit-can or preserving-jar. B is a stopper or lid, which takes over the rim a, and rests upon a gum washer or circular flat band, b. Its rim, c, is bevelled, so as to give it a sharper bearing on the gum, by pressing into it when pressure is applied to the stopper. The top margin of the cap or stopper is cut or formed into two or more cams or elevations and depressions, d d. When the stopper is fitted over the neck or rim a of the jar, a strap, e, of any suitable material, is set over the top of the stopper, at its lowest point, its hooked ends, f f, being placed under the rim or flange g, and its centre, h, inserted into the recess or centre k, formed in the top of the stopper.

It will be readily seen that the strap e is prevented from lifting, by its hooks f taking under the flange g, and therefore, when it is turned, it slides up the sinuosities of the cams d, and thereby forces or wedges the stopper firmly on the gum washer b, making a perfectly air-tight joint.

I at first intended to construct the stopper with inclined edges, the inclinations being in opposite directions diametrically, but found that the strap could only be turned in one direction. If turned oppositely, it was caught by the perpendiculars of the inclined edges, as shown in fig. 4.

What I claim as my invention, and desire to secure by Letters Patent, is—

The combination of the stopper B, elevations and depressions d d, recess k, rim c, clamp e, fulcrum or centre h, packing and seat b b', notched ring g, substantially as and for the purpose described.

In testimony whereof, I hereunto sign my name to this specification in presence of two subscribing witnesses.

JOHN WEIDIG.
